8608½x Benjamin Morris.

Letters Patent.

The schedule referred to in these Letters Patent and making part of the same, containing a description in the words of the said Benjamin Morris, himself of his Improvement in Trunks and Boxes.

To all to whom these presents shall come.

Be it known that I, Benjamin Morris, of New Richmond in the County of Clermont, and State of Ohio, have invented a new and useful improvement in Trunk & Boxes, and that the following is a full and exact description of the construction & use of the said Trunk, Box, and Bath combined as invented by me.

The Trunk may be constructed of wood or leather, and when closed, measures three feet two inches in length, two feet two inches in width, and two feet in depth, being composed of five separate pieces, to wit, - The fall, which forms one entire end of the Trunk, and is let down to the floor by means of hingers, by which it is attached to the bottom or lower part of the body, closes against the top or upper part of the body, where it is secured by an inside lock. The body consists of two square pieces of equal size, being three feet two inches in length, two feet two inches in width, and one foot in depth, one end of each being closed, the other open so that when the upper and lower parts of the body are folded together by means of the hingers, by which they are attached to each other, at the open end fall under the right hand end of the trunk being completely closed and firmly fastened by means of a spring lock at the center of the body. These will consist of which will be made with the best and strongest material in order that they may be strong and durable, the trunk designed to float the same.

with the additional weight of one hundred and eighty pounds (if the trunk be made of light wood) and is placed in the upper part of the body immediately under the top, being three feet long, two feet wide, and eight inches thick. The draw is made of light wood with three tails, and lies under the trunk, being three feet long two feet wide, and eight inches deep.

The Birth and its appendages consist of two rails with a joint in the centre and formed together at the ends with cross pieces to which the head and foot boards, with their uprights for the Musket-bar are attached, by means of hinges and are thereby raised up, and folded down, the uprights folded in rabbits to receive them in the sides of the trunk, by the rails of the Birth. The matress is nailed to the rails and end pieces which thus form the Birth. The entire Birth when completed rests on eight iron hooks or tenants which are with the double purpose of bracing the sides and bottom of the trunk, and are so arranged as to enter the like number of mortises in the under sides of the rails and thus support the Birth.

The settee is a common set when folded up, being two feet two inches long, from eighteen to twenty four inches wide. The back is sixteen inches high, made in two pieces, the upper being seven inches wide and folds down on the lower part which is nine inches wide. The body consists of two pieces of equal size, being four inches deep. The pillows on which it stands are eight inches long, and are placed one on top of the other nine inches. At one end of the settee is a fall which may be let down to the floor by means of rabbits made in the pillars, forming a smooth surface against which the upper part of the body rests, when the settee is unfolded & the Birth laid open. The construction of the Birth with all its appendages, are precisely the same as those described in the Trunk. The other side design of the portable

29

Berth Trunk, is, to accommodate travellers by land & water, but more especially on Steam & Canal Boats; being calculated for a safe conveyance of all such articles as are commonly converged in Trunks, either by land or sea, affording the proprietor at the same time, not only a comfortable bed, on which he may repose at night, with his property, clothing, & under him, but the means of saving himself & property in case of accidents, such as the sinking, or burning of the Boat in which he is travelling, by floating himself & Trunk to shore, by means of the cork provided for that purpose.

Likewise the Berth, if placed in a case made in the form of the body of the trunk, being three feet two inches long, two feet two inches wide, calculated to contain a mattress, bed clothes, & Musketoe bar, & when unfolded is the length of a common bed, and designed to be used in Offices, Colleges, & shops, being a neat & convenient piece of furniture. The litter is also a neat and convenient piece of furniture, and when used as a seat, it occupies but half the space of a common litter, and when unfolded, is a neat and convenient bed, with all the conveniences described above, and is designed for the use of private families, or in the bottoms of steam-boats, and other crafts, affording a seat by day and a bed at night.
